(57) **CLAIM**

The ornamental design for a faucet, as shown and described.

DESCRIPTION

FIG. 1 is a front perspective view of a faucet in accordance with the present design;

FIG. 2 is a front elevational view thereof;

FIG. 3 is a rear elevational view thereof;

FIG. 4 is a right side elevational view thereof;

FIG. 5 is a left side elevational thereof;

FIG. 6 is a top plan view thereof;

FIG. 7 is a bottom plan view thereof;

FIG. 8 is a perspective view of the faucet shown with a sprayer of the faucet in a pulled down configuration

FIG. 9 is a front perspective view of an alternate embodiment of a faucet in accordance with the present design;

FIG. 10 is a front elevational view thereof;

FIG. 11 is a rear elevational view thereof;

FIG. 12 is a right side elevational view thereof;

FIG. 13 is a left side elevational thereof;

FIG. 14 is a top plan view thereof;

FIG. 15 is a bottom plan view thereof; and,

FIG. 16 is a perspective view of the faucet shown with a sprayer of the faucet in a pulled down configuration.

The broken lines shown are included for the purpose of illustrating portions of the article and forms no part of the claimed design.

1 Claim, 16 Drawing Sheets
